UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

FURNACE-DOOR FRAME.

1,118,358.

Specification of Letters Patent. Patented Nov. 24, 1914.

Application filed January 10, 1914. Serial No. 811,390.

To all whom it may concern:

Be it known that I, LUTHER L. KNOX, a citizen of the United States, residing at Avalon, in the county of Allegheny and State of Pennsylvania, have invented a new and useful Improvement in Furnace-Door Frames, of which the following is a full, clear, and exact description, reference being had to the accompanying drawings, forming part of this specification, in which—

Figure 1 is a front elevation partly broken away of one form of furnace door embodying my invention; Figs. 2, 3 and 4 are sections taken, respectively, on the lines II—II, III—III and IV—IV of Fig. 1; Fig. 5 is an enlarged horizontal section through one of the depending leg portions of the structure; Fig. 6 is a section on the line VI—VI of Fig. 5, and Fig. 7 is a perspective view of the bottom connecting or tie member of the structure.

My invention has relation to furnace door frames, and more particularly to hollow water-cooled frames constructed from sheet metal.

The object of my invention is to provide a frame of simple, efficient and durable construction.

In accordance with my invention, the upper or lintel portion of the frame is formed of a front plate 2, and a back plate 3. The front plate 2 has its upper edge portion bent horizontally rearward, as shown at 4, to form the top wall of the structure, being welded at 5 to the upper free edge of the back plate 3. Said front plate also has near each end the outward offset 6, the vertical outwardly offset wall 7 of which forms a door guide. The rear plate 3 has its lower edge portion bent horizontally outward, as shown at 8, to form the bottom wall of the structure, and is welded at 9 to the lower free edge of the front plate 2. This lower wall 8 may be either straight or arched. In the drawing, I have shown it as arched. The back plate 3 also has its edge portions bent forwardly at substantially right angles to form the side walls of the structure, these side walls being welded at 11 to the free vertical edges of the front plate 2.

Each leg portion is formed by a downward extension 12 of the back leg 3 and by a downward extension 13 of the front leg

2. The downward extensions 12 are bent into substantially U-form with the U facing outwardly, as shown in Figs. 4 and 5, while the downward extension 13 fits between the forwardly extending arms of the U and has its free edges welded thereto, as indicated at 11 and 14. This extension has the door-guiding offset 16 therein in alinement with the door-guiding surface 7, and to compensate for this offset, the two legs of the U 65 on the extension 12 are of unequal lengths.

The numeral 17 designates a hollow tie member which connects the legs at their lower ends and which also acts to form the closed bottoms of the legs. This tie member 70 is preferably formed by a single piece of sheet metal shaped and bent in a manner substantially as indicated at Fig. 7, to form the hollow rectangular central portion having open ends, and with the end projections 75 18 of the bottom member thereof. The free edges of the blank are welded on the line 18, and the extensions 18 are welded to the bottom edges of the legs. The inner walls 80 of these legs are shorter than the outer walls and are welded to the top wall of the portion 17. This bottom member forms a substantial tie connection between the lower ends of the legs which effectively prevents 85 their warping or twisting in use.

Any suitable means may be employed for effecting a water circulation throughout the interior of the structure. In the drawing, I have shown a water supply pipe 19, extending vertically downward through one 90 side of the lintel portion and thence into the leg at the corresponding side, the lower end of this pipe being bent horizontally, as shown at 20, within one end portion of the tie member 17. The pipe 19 is also 95 shown as having a perforated branch 21, extending within the lower portion of the lintel over the bottom arch thereof. The heating water rises to an outlet connection 22 at the top of the structure at the opposite side to that where the supply pipe 19 enters.

23 indicates a suitable blow-out plug at the lower end portion of one of the legs, and 24 designates bracing connections, in the form of stay bolts, for the front and back plates.

My invention provides a strong, efficient and durable water-cooled door frame structure which can be readily constructed from 110

sheet metal. The blanks of which the structure is formed can be readily shaped and united by welding, thereby making a practically integral structure of minimum weight.

5 A continuous water circulation may be maintained throughout the structure, thereby rendering it very durable.

I do not wish to limit myself to the exact details of construction and arrangement of 10 the parts, as shown and described, for it is obvious that various changes may be made therein, without departing from the spirit and scope of my invention as defined in the appended claims.

15 I claim:

1. A hollow water-cooled furnace door frame, comprising an upper or lintel portion formed of two sheet metal plates, one of said plates having its edge portions bent 20 to form the side walls of the structure, and the other plate having its free edges united to said side walls and the two plates having downward extensions united to form the hollow leg portions of the structure, substantially as described.

2. A furnace door frame, comprising an upper or lintel portion formed of two sheet metal plates, one of which has its edge portions bent at substantially right angles to 30 form the side walls of the structure, the other plate having its free vertical edges united to said side walls, one of said plates having its upper edge portion bent horizontally and secured to the upper edge of the 35 other plate to form the top wall of the structure, and the second plate having its lower edge portion bent horizontally and secured to the lower edge of the first plate to form the bottom wall of the structure, substantially as described.

3. A furnace door frame, comprising an upper or lintel portion formed of two sheet metal plates, one of which has its edge portions bent at substantially right angles to 45 form the side walls of the structure, the other plate having its free vertical edges united to said side walls, one of said plates having its upper edge portion bent horizontally and secured to the upper edge of the 50 other plate to form the top wall of the struc-

ture, and the second plate having its lower edge portion bent horizontally and secured to the lower edge of the first plate to form the bottom wall of the structure, and said plates having downward extensions united 55 to form the hollow leg portions of the structure, substantially as described.

4. A furnace door frame, comprising an upper or lintel portion formed of two separate sheet metal plates, united to form a 60 hollow box-like structure, each of said plates having downward extensions, the extensions of one plate being bent into U-shape and the extensions of the other plate being secured to the side walls of the U's and closing the 65 open sides thereof, substantially as described.

5. A hollow sheet metal furnace door frame, having a depending leg portion at each side of the door opening, and a hollow bottom member uniting said leg portions, 75 said bottom member having end extensions secured to and forming closures for the lower ends of the legs, substantially as described.

6. A hollow furnace door frame, formed 75 of sheet metal and having depending hollow legs, said legs being united at their lower ends by a hollow transverse tie member having an interior water-circulating space which communicates with the interior space 80 of the legs and having its bottom wall extended to form bottom closures for the legs, substantially as described.

7. A hollow sheet metal furnace door frame having depending hollow legs at each 85 side of the door opening, and a transverse tie member connecting the lower portions of said legs at the bottom of said opening, said tie member having a water circulating space which communicates with the interior spaces 90 of the legs, and having end extensions which are secured to the open lower end portions of said legs to form bottom closures therefor, substantially as described.

In testimony whereof, I have hereunto 95 set my hand.

LUTHER L. KNOX.
